UNITED STATES PATENT OFFICE

RUSSELL E. BENNER, OF MIDDLETOWN, CONNECTICUT, ASSIGNOR TO REMINGTON TYPE-
WRITER COMPANY, OF ILION, NEW YORK, A CORPORATION OF NEW YORK

TYPEWRITING MACHINE

Application filed September 13, 1929. Serial No. 392,327.

My invention relates to typewriting and like machines and more particularly to platens therefor.

It is customary to employ in visible index devices a series of index cards having cut outs and engaging ears or tabs by which an interlocking or connection of the cards with each other may be effected. It is customary to write on these index cards with the aid of a typewriting machine, but difficulty has been encountered in doing this because of the liability of the engaging ears or tabs on the cards fouling with the paper feeding and guiding devices associated with the platen, thus tearing or mutilating the cards and rendering them useless.

One of the main objects of my invention is to overcome these difficulties and provide a platen for typewriting and like machines by which the engaging tabs on index cards may be fully protected against injury in filling in cards on the machine.

A further object of the invention is to provide means of the character specified which are adjustable in order to employ the machine for inscribing cards of different depths.

A still further object of my invention is to provide means of the character specified in which a card may be introduced into an opening in the platen and extend around the platen in either direction and the devices will function equally well in either instance.

To the above and other ends which will hereinafter appear my invention consists in the features of construction, arrangements of parts, and combinations of devices set forth in the following description and particularly pointed out in the appended claims.

In the accompanying drawings, wherein like reference characters indicate corresponding parts in the different views,

Fig. 1 is a front elevation, with parts broken away, of a platen constructed in accordance with my invention.

Fig. 2 is a like view of the same with the outer shell of the platen removed.

Fig. 3 is a detail inside face view of the end stop member and the spring clamping fingers affixed thereto.

Fig. 4 is an enlarged, detail, transverse sectional view of the platen taken on the line 4—4 of Fig. 1 and looking in the direction of the arrows at said line.

Fig. 5 is a like view of the platen taken on the line 5—5 of Fig. 1 and looking in the direction of the arrows at said line.

Fig. 6 is a like view of the platen taken on the line 6—6 of Fig. 1 and looking in the direction of the arrows at said line.

Fig. 7 is a front face view of one form of a visible index card such as may be readily written on in the machine with the aid of the devices of my invention.

Fig. 8 is a like view of one of said cards of a different size that likewise can be readily handled in the machine.

In the present instance I have shown my invention embodied in a detachable platen of a No. 6 Remington Noiseless machine such as is disclosed in my application Serial No. 359,106 filed April 29, 1929. It should be understood, however, that my invention is not restricted to embodiment in such machines, but is applicable to the platens of typewriting and like machines generally, wherever found available.

The platen, in the present instance, comprises a socalled inner shell 1, preferably cylindrical in form and attached by suitable means to the platen heads 2 and 3. The right-hand platen head is connected to the closed end of the shell 1 by screws 4. The left-hand platen head 3 is secured in any suitable manner to the inner shell, as by a drive fit, and is provided with an annular bearing member or collar 5 that is or may be formed integral therewith. The outer cylindrical platen shell 6, at its left-hand end, receives a bearing on the collar 5 and at its right-hand end contains a spacing ring 7 fixed thereto by pins 8. The inner face of this spacing ring receives a bearing on the outer face of the inner shell 1.

In this manner the shells 1 and 6 are maintained spaced apart and mounted for relative rotative adjustment. The extent of such adjustment is limited by a stop pin 9 carried by the shell 1, or the bearing collar 5 thereon, and projecting outward therefrom into a slot

10 cut in the left-hand end of the outer shell 6. The end walls 11 of this slot constitute stops which coact with the stop pin 9 to limit the relative rotative adjustment between the shells 1 and 6 in opposite directions.

In order to normally lock the two shells to turn together I have provided a hand releasable locking device or detent which in the present instance comprises a spring arm 10 fastened at its inner end at 13 to the inner shell 1 and extending at its free end portion through an opening 14 in the closed end of said shell and the platen head 2. The outer end of this spring constitutes a finger piece 15 by which it may be moved towards the axis of the platen against its spring force to release the detent. A locking pin 15 is fixed to the spring 12 and projects out from a side thereof. This pin fits and is adapted to engage in any one of a series of equally spaced locking openings 16 extending around in the inner face of the spacing ring 7, and when in position therein locks the two shells to turn together in any position of their relative adjustment. When the latch or detent is released such relative adjustment may be effected.

The outer platen shell 6 has an unobstructed opening or slot 17 that extends there-through longitudinally of the platen and substantially throughout the length thereof. This slot opens into the space or channel 18 provided between the two shells 1 and 6 by maintaining them spaced apart by the members 5 and 7. A card, such for example as 19 or 20 shown in Figs. 7 and 8 respectively, may be introduced into the slot 17 and have a portion of it received in the channel 18 in either direction around the platen.

When using the platen with cards of the type indicated, it is intended ordinarily that the portion of each card which is cut or slotted, as at 21, and at which the interlocking ears or tabs 2 are provided, shall be received within the platen and covered and protected by the outer shell 6, leaving the uncut portion of the card exposed on the outer surface of the platen, where ordinarily indications are written thereon above the line 23. Now in order to aid in quickly effecting this result and in holding a card in the exact position to which it should be adjusted on the platen with the proper depth of card contained within the platen, I have provided end stops and card clamping devices contained wholly within the platen and arranged beyond the walls of the opening 17, which will now be described.

A sheet, strip or plate 24 of spring metal is secured at 25 intermediate its free edges 26 to the inner platen shell 1 and extends longitudinally throughout a considerable portion of the length thereof. The plate 24 is flexed outward so that the free edge portions 26 thereof are pressed against the inner face of

the outer platen shell, as shown in Fig. 5. Below the free edges 26, the plate is provided throughout its length with off-set portions or shoulders 27 that constitute end stops with which cards that are introduced through the opening 17 in the platen coact. One of said end stops coacts with a card introduced in one direction through said opening, whereas the other end stop coacts with an edge of a card introduced through said opening in the opposite direction.

In order to insure a card being properly arrested against either end stop, depending on the direction it is inserted through the opening 17, and to insure that the card will be held or clamped in place when against an end stop, I have provided the following means within the platen.

A series of spring strips 28 extend around the inner shell 1 between the member 24 and said shell. Each strip 28 is attached intermediate its ends by any suitable means, at 29, to the member 24 and springs outward at its free end. The free end portion of each strip 28 has an inclined portion 30 that crosses the channel 18 and provides a deflecting face that directs the advancing edge of an incoming card towards the outer shell and into cooperative relation with the associated end stop 27. The base of each deflecting member 30 is bent to provide a contact or clamping portion 31 between which and the adjacent free edge portion 26 of the member 24 a card is forced as it is being directed to abutting engagement with the associated end stop 27. This results in clamping the card in its adjusted position and in holding it clamped to the platen in such position as the printing on the card proceeds, enabling, nevertheless, a printed card to be quickly withdrawn and replaced by a new card when desired.

It will be seen that the cards 19 and 20 are of different depths and that it is necessary to insert the card 19 to a greater depth in the platen than the card 20 in order that the ears 22 on the first mentioned card may be received within the platen and be protected from injury. For this reason the relation between the opening 17 in the outer shell of the platen, and the end stops 27 (as well as the spring clamping members 31) attached to the inner shell, is made variable, such variation being brought about by the relative rotative adjustment between the two platen shells 1 and 6 hereinbefore described.

Ordinarily the index cards are inscribed on the top edge portions as hereinbefore pointed out, and as indicated at 32 in Fig. 7. In this event the lower end stop 27 and clamps 31, as the parts are shown in Fig. 5, would come into use and be adjusted for cards of the particular depth in use. In such circumstances only this set of clamps and the associated end stop are required and in such instances the use of the second end stop and as

sociated clamps might be dispensed with. However, it sometimes occurs that it is necessary to write an inscription near the bottom edges of the cards as well as at the top edges.

5 In writing the latter inscriptions it is necessary to employ the second or uppermost end stop 27 (as the parts are shown in Fig. 5) and associated clamping fingers. Therefore, I prefer to employ both sets of said parts at 10 opposite sides of the opening 17 as they contribute to a wider range of use and meet the varying requirements.

Obviously the construction of the present invention may be employed in connection with 15 cards which differ materially from those shown and the manner described of using the construction may be varied.

Various changes may be made, and parts of 20 the construction may be employed without others, without departing from my invention as it is defined in the accompanying claims.

What I claim as new and desire to secure by Letters Patent is:

1. The combination of a cylindrical platen 25 having a card receiving opening therein, and an end stop contained within the platen and against which an edge of a card received through said opening is adapted to abut, said end stop and platen being relatively adjustable to vary the relation between the opening and end stop and thus determine the extent to which the card may be received within the platen.

2. The combination of a cylindrical platen 35 having a card receiving opening therein, an end stop contained within the platen and against which an edge of a card received through said opening is adapted to abut, said end stop and platen being relatively adjustable to vary the relation between the opening and end stop and thus determine the extent to which the card may be received within the platen, and a card clamp adjustable with said end stop and which coacts with a 45 card when arrested by said stop.

3. The combination of a cylindrical platen having a card receiving opening therein, an end stop contained within the platen and against which an edge of a card received 50 through said opening is adapted to abut, said end stop and platen being relatively adjustable to vary the relation between the opening and end stop and thus determine the extent to which the card may be received within the platen, and a spring-pressed card clamp into 55 engagement with which a card is forced as it is brought against said end stop.

4. The combination of a cylindrical platen 60 having an unobstructed card receiving opening therein constantly maintained open for the reception of a considerable extent of a card within the platen, and end stops contained wholly within the platen and arranged on opposite sides of and beyond the walls of 65 said opening and against one or the other

of which stops an edge of a card received through said opening is adapted to abut depending on the direction in which the card is introduced through said opening.

5. The combination of a cylindrical platen 70 having a card receiving opening therein, end stops contained within the platen and arranged on opposite sides of said opening and against one or the other of which stops an edge of a card received through said opening is adapted to abut depending on the direction in which the card is introduced through said opening, and means by which a relative adjustment may be effected between the platen and said end stops to vary the depth the cards 75 may be received in the platen, whether introduced therein from one direction or the other.

6. The combination of a cylindrical platen 80 having an unobstructed card receiving opening therein constantly maintained open for the reception of a considerable extent of a card within the platen, end stops contained within the platen and arranged on opposite 85 sides of and beyond the walls of said opening and against one or the other of which stops an edge of a card received through said opening is adapted to abut depending on the direction in which the card is introduced through said opening, and a card clamp contained wholly within the platen associated with each of said end stops.

7. The combination of a cylindrical platen 90 having a card receiving opening therein, end stops contained within the platen and arranged on opposite sides of said opening and against one or the other of which stops an edge of a card received through said opening is adapted to abut depending on the direction in which the card is introduced through said opening, and means by which a relative adjustment may be effected between the platen and said end stops to vary the depth the cards 95 may be received in the platen whether introduced therein from one direction or the other, and a spring-pressed card clamp associated and adjustable with each of 100 said end stops and with which a card is brought into cooperation as it is brought into abutting engagement with the associated end stop.

8. The combination of a cylindrical platen 105 having a card receiving opening therein, an end stop contained within the platen and against which an edge of a card received through said opening is adapted to abut, said end stop and platen being relatively adjustable to vary the relation between the opening and end stop and thus determine the extent to which the card may be received within the platen, and a locking device that is 110 releasable at will for locking the platen and end stop in their positions of relative adjustment.

9. The combination of an outer cylindrical 115

platen shell having a card receiving opening therein, an inner cylindrical platen shell contained within said outer shell and spaced apart therefrom, means for affording a relative rotative adjustment between said shells, and an end stop carried by said inner shell and with which an edge of a card introduced through said opening in the outer shell is adapted to abut to limit the movement of the card into the outer platen shell.

10. The combination of an outer cylindrical platen shell having a card receiving opening therein, an inner cylindrical platen shell contained within said outer shell and spaced apart therefrom, means for affording a relative rotative adjustment between said shells, an end stop carried by said inner shell and with which an edge of a card introduced through said opening in the outer shell is adapted to abut to limit the movement of the card into the outer platen shell, and a hand released detent for locking said shells to turn together.

11. The combination of an outer cylindrical platen shell having a card receiving opening therein, an inner cylindrical platen shell contained within said outer shell and spaced apart therefrom, means for affording a relative rotative adjustment between said shells, an end stop carried by said inner shell and with which an edge of a card introduced through said opening in the outer shell is adapted to abut to limit the movement of the card into the outer platen shell, and a card clamp carried by said inner shell and associated with said end stop to coact with a card brought into abutting engagement with said end stop whatever be the relative adjustment between said shells.

40 12. The combination of an outer cylindrical platen shell having a card receiving opening therein, an inner cylindrical platen shell contained within said outer shell and spaced apart therefrom, means for affording a relative rotative adjustment between said shells, and end stops arranged on opposite sides of the opening in the outer shell and carried by the inner shell and either one or the other of which stops will coact with a card introduced in said opening depending whether the card is inserted in and moved around the platen in one direction or the other.

13. The combination of an outer cylindrical platen shell having a card receiving opening therein, an inner cylindrical platen shell contained within said outer shell and spaced apart therefrom, means for affording a relative rotative adjustment between said shells, end stops arranged on opposite sides of the opening in the outer shell and carried by the inner shell and either one or the other of which stops will coact with a card introduced in said opening depending whether the card is inserted in and moved around the platen in one direction or the other, and a card clamp

associated with each of said end stops and carried by said inner shell to engage a card inserted in either direction and brought into abutting engagement with the associate end stop.

14. The combination of an outer cylindrical platen shell having a card receiving opening therein, an inner cylindrical platen shell contained within said outer shell and spaced apart therefrom, means for affording a relative rotative adjustment between said shells, end stops arranged on opposite sides of the opening in the outer shell and carried by the inner shell and either one or the other of which stops will coact with a card introduced in said opening depending whether the card is inserted in and moved around the platen in one direction or the other, a spring-pressed card clamp associated with each of said end stops and carried by said inner shell to engage a card inserted in either direction and brought into abutting engagement with the associate end stop, and a hand released locking device for locking both shells to turn together.

15. The combination of an outer cylindrical platen shell having a card receiving opening therein, an inner cylindrical platen shell contained within said outer shell and spaced apart therefrom, means for affording a relative rotative adjustment between said shells, and spring card-clamping fingers carried by said inner shell and each having an inclined deflecting surface that extends substantially from the outer surface of the inner shell to the inner surface of the outer shell in order to deflect a card inserted through said opening in the outer shell to a clamped position between the spring fingers and the outer shell.

16. The combination of an outer cylindrical platen shell having a card receiving opening therein, an inner cylindrical platen shell contained within said outer shell and spaced apart therefrom, means for affording a relative rotative adjustment between said shells, spring card-clamping fingers carried by said inner shell and each having an inclined deflecting surface that extends substantially from the outer surface of the inner shell to the inner surface of the outer shell in order to deflect a card inserted through said opening in the outer shell to a clamped position between the spring fingers and the outer shell, and an end stop carried by said inner shell and with which an edge of a card abuts after it has passed beneath said clamping fingers.

17. The combination of an outer cylindrical platen shell having a card receiving opening therein, an inner cylindrical platen shell contained within said outer shell and spaced apart therefrom, means for affording a relative rotative adjustment between said shells, and a strip of spring metal secured intermediate its ends to said inner shell and terminating at opposite edges on opposite sides of said opening in the outer shell, said spring

metal strip being forced at its edges against the inner wall of the outer shell where each of said edge portions is provided with an off-set that constitutes an end stop for a card inserted through said opening in the outer shell, one or the other of said end stops being brought into use depending on whether the card extends from said opening in one direction or the other around the platen.

10 18. The combination of an outer cylindrical platen shell having a card receiving opening therein, an inner cylindrical platen shell contained within said outer shell and spaced apart therefrom, means for affording a relative rotative adjustment between said shells, a strip of spring metal secured intermediate its ends to said inner shell and terminating at opposite edges on opposite sides of said opening in the outer shell, said spring metal

15 strip being forced at its edges against the inner wall of the outer shell where each of said edge portions is provided with an off-set that constitutes an end stop for a card inserted through said opening in the outer shell, one

20 or the other of said end stops being brought into use depending on whether the card extends from said opening in one direction or the other around the platen, and spring fingers secured to said inner shell and extending on opposite sides of the opening in the outer shell and adjacent to said end stops, said spring fingers constituting card clamps that press towards the inner surface of the outer shell and coact with a card that has

25 an abutting engagement with either of said end stops.

Signed at Middletown, in the county of Middlesex and State of Connecticut, this 10 day of September A. D. 1929.
